CAN FILLING MACHINE

Henry Mondloch, Cedarburg, Wis., assignor to
 Hansen Canning Machinery Corporation, Cedarburg, Wis., a corporation of Wisconsin

Application September 28, 1937, Serial No. 166,136

9 Claims. (Cl. 226—97)

My present invention relates generally to improvements in the art of packing successive batches of commodity in receptacles, and relates more specifically to improvements in the construction and operation of so-called can filling machines of the automatic type.

Generally defined, an object of my present invention is to provide various improvements in automatic can filling machines, whereby the construction and operation is simplified, whereas the efficiency is enhanced to a maximum.

Many different types of can filling machines have heretofore been proposed and are now in use, and in most of the automatic fillers for commodities such as vegetables, fruits and soups, the successive batches of material are accurately measured before being delivered into the successive cans while the latter are being transported at a relatively high rate of speed through the zone of filling. During ordinary and normal operation of a filling machine of the automatic type, the supply of empty cans is continuous, and an uninterrupted procession of cans is advancing through the zone of delivery of the measured batches of commodity from the measuring mechanisms. However, the supply of cans is occasionally broken by failure on the part of an attendant or of the supply mechanism to provide an uninterrupted train of the containers; and it also becomes desirable when starting such a filling machine or when changing grades, to pass a single test can through the filling zone. If the measuring pockets are permitted to receive commodity from the source of supply and to deliver the charges when no receptacle is in place, considerable material is wasted and unsanitary conditions prevail, and in order to avoid such undesirable consequences, a number of attempts have heretofore been made to provide so-called no-can-no-fill devices which were intended to prevent discharge of measured batches when no cans were in position to receive the same. These prior safety devices for eliminating waste of product, have either been too complicated or too unreliable in action, and were therefore relatively unsatisfactory. It is also often desirable in can filling machines, to have the can supply and discharge mechanisms located closely adjacent to each other and as far from the commodity supply hopper or source, as possible in order to facilitate handling of the empty and food laden receptacles, while preventing spilling and splashing of the commodity upon the cans. The prior machines ordinarily have the supply hopper located so that it interferes either with the

empty can supply, or with the loaded can delivery mechanism, and this disposition of the elements becomes even more objectionable when a no-can-no-fill mechanism is also used.

It is therefore a more specific object of my present invention to provide improved no-can-no-fill mechanism for an automatic receptacle filling machine, which mechanism is simple, compact and durable in construction, and is moreover highly efficient and dependable in operation.

Another specific object of the invention is the provision of an improved can filling assemblage which is capable of automatically and rapidly withdrawing accurately measured quantities of fluent commodity from a stationary supply source, and of delivering the measured batches to successive receptacles, but which will not effect measuring or delivery of charges when no cans are being supplied to the filling zone.

A further specific object of this invention is to provide a simplified and compact driving assemblage for the various elements of a can filling machine, which will permit operation at high speeds without wasting commodity or damaging relatively frail containers such as tin cans.

An additional specific object of the invention is to provide improved commodity measuring and discharge mechanism which is adapted to handle various kinds of materials, and to deliver all portions of the measured batches to the successive containers in a most effective manner.

Still another specific object of my invention is to provide an improved filler which is operable at high speed with minimum noise and vibration, and wherein the can feed mechanisms and the supply hopper are most desirably disposed.

Another specific object of this invention is the provision of a sturdy can filling assemblage which is reliable and automatic in operation, which may be manufactured and operated at moderate cost, and which has enormous capacity.

These and other specific objects and advantages of my present invention will be apparent from the following detailed description.

A clear conception of embodiments of the various features constituting my present invention, and of the mode of construction and of operating can filling machines embodying the improvements, may be had by referring to the drawings accompanying and forming a part of this specification wherein like reference characters designate the same or similar parts in the several views.

- Fig. 1 is a central vertical section through the upper portion of a twelve pocket automatic can filling machine embodying some of the improvements;
- 5 Fig. 2 is a top view of the measuring mechanism and material supply hopper of the filling machine of Fig. 1, the can supply and discharge mechanisms having been omitted for the sake of clearness;
- 10 Fig. 3 is a somewhat reduced top view of the can handling mechanism, showing also the automatic no-can-no-feed attachment and the elements for transmitting motion to the various movable parts of the machine from a common drive shaft;
- 15 Fig. 4 is a fragmentary irregular radial section through the filler, the upper portion of the section being taken radially through the stationary material supply hopper, while the lower portion is taken radially and centrally through 20 the empty can supply mechanism;
- Fig. 5 is a development of the tracks for normally actuating the measuring plungers and for preventing measuring movement thereof when no receptacles for the charges are present;
- 25 Fig. 6 is a fragment of the track development of Fig. 5, showing the operation thereof when no can is presented for filling;
- Fig. 7 is a top view of the no-can-no-feed mechanism alone, showing the position of the elements during normal operation of the filler;
- 30 Fig. 8 is a fragmentary top view of the cup-shaped measuring casing and of the mechanism shown in Fig. 7, with the elements moved to a position corresponding to that when no cans are 35 being supplied to the machine;
- Fig. 9 is a side elevation of the can engaging arm and the actuating spring and mounting thereof;
- 40 Fig. 10 is a top view of a modified seven pocket can filling machine of the same general type as that of Figs. 1 and 2, showing the improved location of the supply hopper with respect to the can supply and discharge mechanisms; and
- 45 Fig. 11 is an irregular vertical section through the machine of Fig. 10, the right half of the section being taken radially through the commodity supply hopper, and the other half being taken radially through the empty can supply mechanism.
- 50 While the invention has been shown and described herein as being specifically embodied in rotary automatic plunger type can fillers having a specific number of measuring pockets, it is not the intent to thereby unnecessarily restrict the 55 scope and utility of the improved features.
- Referring generally to Figs. 1 to 4 inclusive, the improved can filling machine shown therein comprises in general a main frame 14 having a horizontal medial can support 15 and upper and 60 lower transverse bearing elements 16, 17 respectively; an upright central shaft 18 journaled in the support 15 and in the elements 16, 17; a cup shaped casing 19 fixedly mounted upon the main frame 14 between the support 15 and the element 16 and having a large bore 20 formed concentric with the shaft 18, and supporting a stationary commodity supply hopper 21 which communicates with the lower portion of the bore 20; a measuring pocket member 22 snugly fitting the casing 70 bore 20 and being drivingly connected to the shaft 18 by means of a driving head 23; a series of parallel vertically reciprocable plungers 24 slidable within cylindrical pockets 25 formed in the member 22, and each having a shoe 26 slidably cooperable with the casing bore 29; rollers 75
- 27 carried by the plungers 24 and coacting with a cam track 28 secured to the fixed casing 19 to normally reciprocate the measuring plungers 24; an annular series of can hooks 29 carried by the shaft 18 beneath the casing 19 and coacting with a can guide 30 to transport the successive cans 31 around the shaft 18 over the can support 15 and beneath the material delivery slot 32 of the casing 19; empty can supply mechanism including a can guide 33 and a can feed screw 34; 10 loaded can delivery mechanism including a support 35 and a rotor 36; a main horizontal drive shaft 37 journaled in the main frame 14; motion transmitting mechanism connecting the shaft 37 with the upright shaft 18 and with the 15 can supply, transporting and discharge devices; and improved no-can-no-fill mechanism interposed between the empty can supply mechanism and the cam track 28.
- The upper and lower bearing elements 16, 17 20 are firmly but detachably secured to the frame 14 and provide upper and lower bearings for maintaining the shaft 18 in upright position, and the member 19 is also firmly attached to the side portions of the frame 14 so as to maintain the bore 20 concentric with the axis of the shaft 18. It should be noted, that the entire machine may be readily dismantled for inspection and cleaning, upon removal of the upper bearing element 16, and this element can be quickly removed by 25 releasing the hand clamping nuts 38, see Fig. 1. The measuring pocket member 22 and the plungers 24 which are slidably confined within the parallel vertical bores 25 thereof, are 30 revolvable as a unit within the enlarged bore 20 of 35 the casing 19 by the shaft 18 through the driving head 23, but all of these parts may be readily lifted out of the cup-shaped casing 19 when the bearing element 16 has been removed. The upper end of the casing 19 has a plane annular 40 surface 39 portions of which cooperate with the cam track 28 to provide a continuous annular track for raising and lowering the plungers 24 through the rollers 27 during normal operation of 45 the machine.
- A portion of the cam track 28 is vertically adjustably suspended from the fixed casing 19 by means of parallel upright posts 40, and the entire track is normally held in place by bolts 41 as shown in Figs. 2, 5, 6 and 7. The track 28 comprises successive sections 42, 43, 44, 45, 46, 47 of which the sections 42 and 46 are swingably mounted while all other sections 43, 44, 45 and 47 are normally fixed. The track sections 43, 44, 45 are formed integral with each other and are 50 simultaneously vertically adjustable with the posts 40 to vary the extent of elevation of the successive plungers 24 and hence the volume of each measured batch, by means of mechanism comprising a set of pinions 48 secured to an adjusting shaft 49 and coacting with racks formed on the posts 40. These simultaneously adjustable sections 43, 44, 45 are, however, normally locked in adjusted position by nuts 50 coacting with the adjacent bolts 41 as shown in Fig. 5. 55 The swingable gate section 42 of the cam track, constitutes a part of the improved no-can-no-fill mechanism, and is swingably suspended from the casing 19 by means of a vertical pivot 51 which is preferably located as near to the roller track 70 as possible, as clearly shown in Figs. 2, 7 and 8. The track section 42 is inclined from the casing surface 39 to the lower end of the track section 43, and when the section 42 has been swung inwardly against the casing 19 as in Fig. 7, the 75

rollers 27 will ride upwardly along the section 42 onto the section 43, whereas outward displacement of the section 42 to the position shown in Fig. 8 will cause the advancing rollers 27 to merely travel in a horizontal plane along the casing surface 39. The upwardly inclined track section 43 causes the successive rollers 27 advancing therewith, to elevate the successive measuring plungers 24 so as to draw successive charges of material from the supply hopper 21 through the inlet opening 52 into the measuring chambers 25, and the subsequent recessed track section 44 cooperates with its top guide 53 to cause each of the successive plungers 24 to slightly compress each measured batch of material before communication with the supply hopper 21 through the opening 52 has been interrupted, and before communication with the discharge opening 32 has been established. The downwardly inclined track section 45 is normally aligned with the subsequent sections 46, 47, and this section 45 cooperates with a top guide 54 to force the successive plungers 24 downwardly after communication between the measuring chambers 25 and the opening 32 has been established. The movable track section 45 is pivotally suspended to swing vertically about a horizontal pivot 55, and this section is normally held in the position shown in Fig. 5, by gravity, but may be lifted as in Fig. 5, by a roller 27 advancing upwardly from the casing surface 39 along the upwardly inclined fixed track section 56. The fixed section 56 is formed integral with the final downwardly inclined fixed section 47 and the latter has a top guide 57 which cooperates with the successive plunger rollers 27 to finally expel all of the measured material from the chambers 25 through the discharge opening 32. It is to be noted, that the top guide 54 of the vertically adjustable track section 45 has a slightly tapered end portion 58 which cooperates with the adjacent end of the top guide 57 so as to insure continuity of the guide track for various positions of vertical adjustment of the track sections 43, 44, 45.

The can hooks 29 are detachably secured to the upright shaft 18 beneath the cup-shaped casing 19, and the can support 15 may be provided with an annular can rest 59 along which the successive cans 31 are normally transported by the hooks 29. The rest 59 may be of any desired thickness so as to bring the successive can tops close to the bottom of the casing 19, and the lower end 60 of each plunger 24 may be tapered as shown in Figs. 1 and 4 so as to snugly coact with a tapered portion 61 at the lower end of each chamber or pocket 25 and to thereby insure complete delivery of each measured batch. The can guide 33 of the empty can supply mechanism is secured to the can support 15, and is formed to right the successive empty cans 31 and to deposit the same into the zone of action of the can feed screw 34, which functions to deliver the successive cans into the path of revolution of the hooks 29. The loaded can delivery support 35 is likewise secured to the fixed can support 15, and the can discharge rotor 36 is secured to a vertical drive shaft 62 and cooperates with the hooks 29 to gently remove the successive loaded cans 31 from the filling zone.

The motion transmitting mechanism for transmitting power from the main drive shaft 37 to the various movable portions of the machine, includes the shaft 37 which is journaled in the main frame 14 beneath the can supply and discharge mechanisms, and which may be driven from any suitable power source and at any desirable speed. The main shaft 37 is drivingly connected by a chain drive 63 to a horizontal counter shaft 64 as indicated in Figs. 1 and 3, and the shaft 64 carries a bevel gear 65 which meshes with another bevel gear 66 secured to a vertical counter shaft 67. The vertical shaft 67 also carries a pinion 68 which meshes with a spur gear 69 secured to the central vertical shaft 18, thus imparting continuous rotation to this shaft 10 and to the pocket member 22 and can hooks 29 which are secured thereto. A second bevel gear 70 which also meshes with the bevel gear 66, is secured to and drives a third counter shaft 71 which carries another bevel gear 72 and a worm 15, see Fig. 3. The bevel gear 72 meshes with an additional bevel gear 74 which constantly revolves the can feed screw 34; and the worm 15 meshes with a worm wheel 75 secured to the shaft 62 so as to constantly revolve the can discharge rotor 36 in step with the can hooks 29. The bevel gear 74 is secured to one end of a horizontal shaft 76 journaled beneath the can feed screw 34, and the opposite end of this shaft 76 carries a spur gear 77 which meshes with a spur gear 78 secured to the feed screw drive shaft 79 which is also provided with a hand wheel 80. Motion will thus be simultaneously imparted from the shaft 37 to the can feed screw 34, the can hooks 29, the can discharge rotor 36, and to the material measuring mechanism.

The improved no-can-no-fill mechanism which includes the gate cam 42 of the cam track 28, also comprises a lever 81 carried by a pivot 82 supported by an adjustable bracket 83; levers 84, 85 secured to the pivots 81, 82 respectively; a connecting rod 86 of variable length connecting the swinging ends of the levers 84, 85; and a spring 87 embracing the pivot 82 and coacting with the bracket 83 and with the lever 81 to constantly urge the latter into the path of the entering empty cans 31, see Figs. 3, 7, 8 and 9. The bracket 83 is adjustably attached to the can feed guide 33 so as to permit adjustment in or out in order to accommodate cans 31 of different diameters, and the rod 86 is variable in length by means of a turn buckle 88 so as to insure proper coaction of the gate cam 42 with the roller track 28. The can engaging lever 81 is positioned to coact with the lower portions of the successive cans, and when no can is present, the lever 81 will remain in the position shown in Fig. 8 by virtue of the action of the spring 87, and the gate cam 42 will then remain out of contact with the casing 19 and will permit the roller 27 of 55 the corresponding plunger 24 to merely ride along the casing surface 39 without elevating the plunger and sucking in a charge of material from the feed hopper 21.

While the normal operation of the improved automatic can filling machine shown in Figs. 1 to 9 inclusive should be apparent from the detailed description of the various parts thereof, this operation will again be briefly described. When the machine is operating normally, motion 60 is being transmitted from the main drive shaft 37 to the various movable parts, and the successive empty cans 31 are being delivered in regular and uninterrupted succession by the feed screw 34 to the can hooks 29. As each can 31 passes 70 the lever 81, it forces this lever from the position shown in Fig. 8, outwardly into the position shown in Fig. 7, thereby causing the gate track or cam 42 to connect the surface 39 with the upwardly inclined initial fixed cam track section 75

43. The roller 27 of the measuring plunger 24 which corresponds to the passing can 31, will then ride along the gate track 42 and the upwardly inclined track section 43 as the can proceeds along the guides 33, 36; and as soon as this can leaves the lever 81, the latter will be swung inwardly by the spring 87 and the gate track 42 will be positioned as in Fig. 8. The roller 27 advancing upwardly along the track sections 42, 43 raises 10 the corresponding plunger 24 and draws a quantity of material from the hopper 21 into the corresponding advancing measuring chamber 25. When the highest point of the track section 43 has been reached, communication between the 15 measuring pocket 25 and the hopper 21 through the inlet opening 52 will be cut-off, and just prior to such cut-off the plunger 24 will be slightly depressed to compress the measured and confined batch of material, by coaction of the roller 27 with the track section 44 and top guide 53. The 20 roller will then advance to the downwardly inclined cam track section 45, and as soon as the highest portion of the section 45 has been reached, the measuring pocket will be brought into communication with the arcuate discharge opening 32 beneath which the can 31 is then being conveyed by the hooks 29. During the subsequent advancement of the roller 27 downwardly along the aligned track sections 45, 46, 47, the plunger 25 will be lowered by the top-guides 54, 57 co- 25 acting with the roller 27, and the measured batch of material will be forced through the opening 32 into the can 31. As the roller 27 finally approaches the casing end surface 39, the tapered plunger end 60 coacts with the tapered pocket bottom 61 to insure expulsion of every particle of material, and the V-shaped end of the discharge opening will ultimately prevent dripping of material after the food laden can 31 has been 30 carried beyond this opening. The can hooks 29 subsequently deliver the loaded can 31 to the rotor 36 which effects final discharge in the usual manner. The successive cans 31 are thus automatically supplied, filled with accurately measured batches of material, and delivered from the machine, without the slightest waste of material or injury to the frail cans, even when operating at very high speed.

Now let us assume that the can supply is interrupted, or that the operator wishes to fill only a single can. When no can 31 is brought into engagement with the lever 81 by the feed screw 34, the spring 87 will obviously hold the lever 81 and the gate cam or section 42 in the position shown in Fig. 8. The successive plunger actuating rollers 27 will then roll past the section 42 and along the horizontal casing surface 39 beneath the track sections 43, 44, 45. While the rollers 27 are advancing along the surface 39, the plungers 24 will not be lifted and no material will be drawn into the chambers 25 as the pockets are carried past the supply opening 52. Upon reaching the upwardly inclined fixed track section 56, the rollers 27 will elevate the pivotally mounted track section 46 and will ride there beneath onto the final downwardly inclined track section 47. Due to the fact that the measuring chambers 25 are open to the atmosphere through the opening 32 at this time, no material will be 50 admitted, and the plungers 24 will subsequently be lowered by the advancement of the rollers 27 along the section 47 and top-guide 57 so as to place them in position for future measuring. It will thus be noted that when no can 31 passes 55 the lever 81, no measuring of a batch is effected,

and no delivery of a measured charge can take place.

In the can filling machine of Figs. 1 to 9 inclusive, twelve measuring pockets 25 are used and the supply hopper 21 is disposed directly above the can feed and discharge mechanisms. When operating with some commodities such as soups, such location of the hopper is not desirable due to interference and possible splashing, and the machine may then be constructed as shown in the 10 seven pocket filler of Figs. 10 and 11. This machine is generally similar to that illustrated in Figs. 1 to 9, and comprises a main frame 84 having a can support 85 and a lower bearing element 87; an upright central shaft 88 journalled in the 15 support 85 and element 87; a cup-shaped casing 89 fixedly mounted upon the upper portion of the frame 84 above the support 85 and having a large bore 90 formed concentric with the shaft 88, the casing 89 providing a support for a stationary commodity supply hopper 91 which communicates with the lower portion of the bore 90 through a horizontal duct 86; a measuring pocket member 92 snugly fitting the casing bore 90 and being drivingly connected to the shaft 88 by a 20 driving head 93; a series of parallel vertically reciprocable plungers 94 slidable within cylindrical pockets 95 formed in the member 92, and each having a shoe 96 slidably cooperable with the casing bore 90; a roller 97 carried by the upper 25 end of each plunger 94 and coacting with a cam track 98 secured to the fixed casing 89, to normally reciprocate the plungers 94 within the pockets 95; an annular series of can hooks 99 secured to the shaft 88 and cooperating with a 30 fixed can guide 100 to transport the successive cans 31 beneath the material discharge opening 102 of the casing 89; empty can supply mechanisms including a can guide 103 and a can feed screw 104; loaded can delivery mechanism including a guide 105 and a conveyor 106 located closely adjacent to the supply mechanism; and motion transmitting mechanism for driving the various parts.

While the improved no-can-no-fill mechanism 45 has been omitted from this modified can filling machine, it may also be utilized, but the main difference between the two machines is the relative disposition of the can supply and discharge mechanisms with respect to the commodity supply hopper. In the machine of Figs. 10 and 11, the can supply and discharge mechanisms are located closely adjacent to each other on one side of the filler, whereas the material supply hopper 91 is located at the extreme opposite side of the apparatus remote from the can admission and delivery mechanisms. The supply hopper 91 thus avoids obstruction to or interference with the can handling mechanisms, and the commodity may be dumped into the hopper without danger of splashing material onto the can feed and discharge. The horizontal duct 86 which extends from within the side members of the frame 84 to the lower end of the hopper 91 is of considerable length and may be so formed that the hopper can be disposed a considerable distance from the casing 89 in order to further facilitate admission of fresh commodity. Otherwise, the modified machine is substantially the same in construction and operation, as the filler of Figs. 1 to 9 inclusive, the plungers 94 being operable by the rollers 97 coacting with the cam track 98 to accurately measure and deliver successive measured batches to the successive cans 31 being transported through the filling zone by the can hooks 99. 75

From the foregoing detailed description of the construction and operation of my improved can filling machines, it will be apparent that the invention provides an automatic can filling assembly which may be operated at relatively high speed in a sanitary manner without wasting material or danger of damaging the successive relatively frail cans. The improved no-can-no-fill mechanism is relatively simple and compact in construction and is also dependable in operation. This mechanism will permit filling of individual cans for trial purposes, by merely manipulating the hand wheel 80, and will also function with the greatest precision to avoid measuring batches of material when no cans are delivered to the filling zone during normal operation of the machine. The no-can-no-fill mechanism can also be adjusted to cooperate with cans of different sizes, and does not in any manner interfere with the normal operation of other parts of the machine. The improved construction of the plungers and measuring pockets with correspondingly tapered lower ends, insures delivery of all portions of the measured batches, and the formation of the discharge opening in the cup-shaped casing eliminates undesirable dripping. The frame assemblage with bearings above and below the measuring pocket member provides a stable machine wherein chattering and vibration is eliminated, and the adjusting mechanism for the cam track permits convenient variation in the volumes of the measured charges. The location of the material supply hopper on the side of the machine opposite to the can feed discharge mechanisms has also been found extremely advantageous in facilitating the handling of the cans and in eliminating splashing of commodity upon the exteriors of the cans. The location of the pivot for the swingable gate section of the cam track has been found to be extremely important, since the rollers 27 in advancing up the incline of this gate section, normally tends to push the track section away from the cup-shaped casing. By locating the pivot of this section closely adjacent to the annular wall of the cup-shaped casing, the rollers 27 in fact tend to hold the gate section in position, until after the rollers have proceeded to the fixed track section 43. This action is advantageous since it tends to remove all pressure from the cans entering the machine, thus positively avoiding damaging the relatively frail cans. The improved machine has proven highly successful in actual commercial use and has also proven extremely dependable as compared to prior machines of the same general type.

It should be understood that it is not desired to limit this invention to the exact details of construction or to the precise mode of operation, herein shown and described, for various modifications within the scope of the claims may occur to persons skilled in the art.

I claim:

1. In a can filling machine, a fixed casing having a bore and a plane upper end surface, a member rotatable within said bore and having a series of measuring pockets therein, a plunger reciprocable in each of said pockets to introduce and discharge measured batches of material, a cam track cooperable with said surface to reciprocate said plungers, said cam track having a gate section movable laterally toward and away from said surface, means for conveying cans in succession, beneath said pockets, means for feeding cans to said conveying means, and a lever oper-

able by the cans passing through said feeding means, said lever being cooperable with said movable cam section to move the latter away from said surface when no can engages the lever.

2. In a can filling machine, a casing having a bore and a plane annular end surface, a member rotatable within said bore and having a series of measuring pockets therein, a plunger in each of said pockets, a cam track cooperable with said surface and with the successive plungers to cause the latter to introduce material into said pockets and to deliver said material therefrom, said cam track having a gate section pivotally supported closely adjacent to said surface, means for conveying cans in succession beneath said pockets, means for feeding cans to said conveying means, and a lever movable by the successive cans passing said feeding means and being cooperable with said gate section to move the latter out of cooperative relation with said plungers. 20

3. In a can filling machine, an annular stationery casing having a plane upper surface, a measuring pocket member revolvable within said casing, a plunger movable in each pocket to introduce and deliver batches of material, each of said plungers having an actuating element cooperable with said plane surface while said plunger is in inactive position, a cam track with which said plunger actuating elements are cooperable to move said plungers, said track having a movable section for guiding said elements from said plane surface upon said track, and means operable when no cans are being delivered to the zone of discharge of material by said plungers for maintaining said elements in contact with 35 said plane surface.

4. In a can filling machine, a casing having a bore and an annular plane surface adjoining said bore, a measuring pocket member revolvable in said bore, a plunger in each of said pockets, an actuating roller for each plunger cooperable with said plane surface to hold the corresponding advancing plunger in inactive position, a cam track cooperable with said rollers to normally move said plungers, said track having a movable section formed to either guide said rollers along said track or to permit the same to continue advancing along said plane surface, and means operable by the entering cans for placing said movable track section in said guiding position. 50

5. In a can filling machine, a casing having a bore and an annular plane surface adjoining said bore, a measuring pocket member revolvable in said bore, a plunger in each of said pockets, an actuating roller for each plunger cooperable with 55 said plane surface to hold the corresponding advancing plunger in inactive position, a cam track cooperable with said rollers to normally move said plungers, said track having a laterally swingable gate section formed to guide said rollers along 60 said track when in innermost position and to permit the same to ride along said plane surface when swung outwardly away from said casing, and means operable when no cans are entering to swing said gate section outwardly. 65

6. In a can filling machine, a revolvable measuring pocket member, a supporting frame for said member coacting with diametrically opposite sides thereof, a series of plungers movable within the pockets of said member to measure and deliver successive batches of material, a material supply hopper for admitting material to said pockets from a zone laterally of said frame and at one side of the axis of revolution of said member, and can feed and discharge mechanisms 70 lo- 75

cated laterally of said frame at the opposite side of said axis for admitting and discharging cans to the zone of delivery of the measured batches.

7. In a can filling machine, a revolvable measuring pocket member, a supporting frame for said member extending toward the same at diametrically opposite sides thereof, plungers movable within the pockets of said member to measure and deliver successive batches of material, a material supply hopper having an admission opening disposed laterally of said frame and at one side of the axis of revolution of said member, and can feed and discharge mechanisms located laterally of said frame closely adjacent to each other on the opposite side of said axis.

8. In a can filling machine, an annular casing having a bore and a plane end surface, a member rotatable within said bore and having a series of measuring pockets therein, a plunger movable in each of said pockets to introduce and discharge batches of material, a cam track cooperable with said surface to move said plungers, said track having a gate section movable toward and away from said surface, means for transporting cans

in succession in close proximity to said pockets, means for feeding cans to said transporting means, and a lever operable by the cans passing through said feeding means, said lever being cooperable with said movable cam track section to move the latter away from said surface when no can engages the lever.

9. In a can filling machine, a fixed casing having a bore and a continuous annular end surface, a member having a series of measuring pockets revolvable within said casing, a plunger reciprocable within each of said pockets to introduce and discharge batches of material, a cam track cooperable with said surface to reciprocate said plungers, said track having a gate section swingable laterally toward and away from said surface, means for transporting cans in succession in close proximity to said pockets, means for feeding cans to said transporting means, and a lever operable by the cans passing through said feeding means, said lever being cooperable with said movable cam track section to move the latter away from said surface when no can engages the lever.

HENRY MONDLOCH.
